[57] CLAIM

The ornamental design for a portable control housing for a gas purging system, as shown and described.

DESCRIPTION

FIG. 1 is a top, front, and right side perspective view of a portable control housing for a gas purging system showing our new design;

FIG. 2 is a left side elevational view, the right side elevational view being a mirror image;

FIG. 3 is a front elevational view;

FIG. 4 is a rear elevational view;

FIG. 5 is a top plan view; and

FIG. 6 is a bottom plan view thereof.

UNITED STATES PATENT AND TRADEMARK OFFICE
CERTIFICATE OF CORRECTION

PATENT NO. : DES. 309,584

DATED : JULY 31, 1990

INVENTOR(S) : JAGADISAN KRISHNAMURTHY; NOLAND E. VOGT

It is certified that error appears in the above-identified patent and that said Letters Patent is hereby corrected as shown below:

First page, column 1, name of Assignee reads:
Semi-jGas Systems, Inc. - Should read "Semi-Gas Systems, Inc."

Signed and Sealed this
Twenty-ninth Day of October, 1991
